UNITED STATES PATENT OFFICE.

WILLIAM THUMM, OF CHICAGO, ILLINOIS.

WATER-SEAL VALVE.

1,141,668.

Specification of Letters Patent.

Patented June 1, 1915.

Application filed March 2, 1914. Serial No. 822,083.

To all whom it may concern:

Be it known that I, WILLIAM THUMM, a citizen of the United States, residing at Chicago, in the county of Cook and State of Illinois, have invented certain new and useful Improvements in Water-Seal Valves, of which the following is a specification.

The present invention relates to valves arranged and adapted to be attached to a radiator or other heating element for the purpose of permitting the escapement of air from the radiator, and for preventing the undue escapement of steam therefrom.

The objects of the present invention are to provide a valve of the class above specified which is cheap and simple of construction; to so arrange the various parts of the valve as to enable the same to be easily adjusted or arranged to permit of a blowing out of the system; to provide means for venting the air from the valve casing; to provide means for adjusting the degree of opening in the venting means; and to so arrange the interior parts of the valve as to provide a water seal which will act to prevent undue escapement of steam from the radiator into the return pipe of the system.

The invention further consists in the features of construction and combinations of parts hereinafter described and claimed.

In the drawings: Figure 1 is a longitudinal section of the valve of the present invention showing the parts thereof in normal operative position; Fig. 2 is a view similar to Fig. 1 but showing certain portions of the valve in elevation and showing the interior mechanism of the valve adjusted or arranged to permit of a blowing out of the system; Fig. 3 is a section on line 3—3 of Fig. 1 looking in the direction of the arrows; Fig. 4 is a sectional detail of the air vent showing the same in closed or inoperative position; and Fig. 5 is a view similar to Fig. 4 showing the vent open and in inoperative position.

The present invention, as stated, is intended and adapted for attachment to a radiator or other heating member to permit the venting of air therefrom and the conveying of steam therein. The valve is more particularly adapted for use with low pressure systems and the theory of operation is to form a body of water therein which will act as a water seal to prevent the escape of steam from the radiator into the return pipe of the system.

Referring now to the drawings, and particularly to Figs. 1 and 2, the device as there illustrated is shown in conjunction with a casing 6 which may be of any form and size, and the said casing illustrated is provided with a neck 7 at its lower end, which neck is formed with a passage 8 which constitutes the outlet from the casing. This outlet passage is placed in communication with the return pipe of the system. A neck 9 is also provided on said casing and is located as shown intermediate the upper and lower edge thereof and this neck 9 is formed with a passage 10 which communicates with the interior of the radiator, and a suitable coupling is provided for connecting the casing to the radiator.

The interior mechanism of the valve consists of a sleeve 12, a tubular member 13, and air vent mechanism 14^a. The sleeve 12, as shown, is attached to a member 14 which is threaded into the upper end of the casing, and this member is provided with a shoulder 15 which rests against the upper edge of the casing and forms a steam tight joint to prevent leakage of steam at this point. This member in the construction shown may be said to constitute a portion of the cap piece which closes the upper end of the casing and constitutes the carrying member for the sleeve 12, as will be seen from the drawings the sleeve 12 terminates short of the floor of the casing leaving a space between its end and the said floor.

The tubular member 13, as will be seen from Fig. 1, is adapted to have its lower end 16 entered into the upper portion of the passage 8, and the said lower end 16 is arranged to have a sliding fit with respect to the walls of said passage. This member 16 is provided with an opening or openings 17 located intermediate its extremities and through these openings the water of condensation and air passes from the interior of the casing through the bore or passage in said member and into the discharge passage. The tubular member is carried by a head-like member 18 which, as shown, has a threaded engagement with the member 14, and when the tubular member is positioned as in Fig. 1, the member 18 has its upper portion seated on the upper portion of the member 14 whereby the members 14 and 18 combine to form a complete cap or closure for the open upper end of the casing.

The object in forming the carrying mem-

ber 18 for the tubular member in a manner so that it can be moved independently of the movement of the member 14 and sleeve 12, is to easily and quickly permit the parts 5 to be adjusted into proper position to permit blowing out of the system.

The term "blowing out of the system" is meant to indicate the following operation: When a heating system is first installed the 10 pipes, radiators, etc., have a certain amount of sand or grit adhering to the inner surfaces thereof which is left after the casting operation. If this sand and grit is not expelled from the interior of the pipes and radiators during the initial operation of the 15 system it will continue to circulate through the system for a substantial period of time and will grind or wear the valves thereof in an undesirable manner, and hence it is customary 20 when the systems are first installed to open up the valves and blow steam through the system for the purpose of carrying off and eliminating the sand and grit from the interior of the pipes and radiators. 25 The system could not be blown out with the interior portions of the valve in the position shown in Fig. 1, since the direct discharge from the lower end of the casing into the return pipe would not be obtained and the 30 dirt or sediment blown from the radiator would merely collect in the lower part of the casing. Also the cap or cover closing the upper end of the casing must not be removed or substantially withdrawn from 35 closing position since if this were done the dirt, sediment and steam incident to the blowing out operation would be discharged and scattered over the room in an undesired manner, and moreover owing to such leakage, 40 steam could not be forced through the system in a manner to efficiently remove the dirt or sediment.

In the present invention means have been provided to position or arrange the interior 45 portions of the valve whereby this blowing out process may be accomplished without removing the closure for the open end of the casing and at the same time permit a direct discharge from the lower portion of 50 the interior of the casing into the return pipe of the system. This arrangement is effected by turning the member 18 a distance to bring the lower end 16 of the tubular member 13 out from engagement with the 55 walls of the outlet 8 and clear of said outlet; that is the tubular member is brought into a position similar to the position shown in Fig. 2 of the drawings. It is evident from a 60 study of said figure that a free, clear and direct passage is provided between the lower portion of the interior of the casing and the outlet 8, and it is also clear that in providing such free passage the open upper end of the casing is maintained in a closed condition 65 whereby no leakage of steam etc. at this

point is permitted. The adjustment of the parts from the position shown in Fig. 1 to the position shown in Fig. 2 or vice versa is a simple and quick operation, and, therefore, this blowing out operation can be accomplished with the valve of the present invention in a simple and quick manner and without any inconvenience or objectionable disorganization of the valve parts.

Referring now to the air vent mechanism 75 which is shown more in detail in Figs. 4 and 5, this consists of a plug 19 provided at one end with a head 20 and at its opposite end with an exterior threaded surface 21. This threaded surface meshes and engages with an interior threaded surface of a tube 22 formed integral with or secured to the sleeve 12 adjacent the upper end of said sleeve. The interior bore of this tube 22 is increased 80 for a portion thereof as at 23, a cross bore or cross bores 24 are formed in said plug and extending partially through the plug and communicating with the cross bores 24 is an axial or longitudinal bore 25. The head 26 is provided with a seating face 27 which when the vent is closed seats against the inner end 28 of the tube 22. With the parts as shown in Fig. 4 it is obvious that no 85 passage of air is permitted from the exterior to the interior of the sleeve 12 through the vent. But with the parts shown in Fig. 5 the head 26 is out of seating engagement with the end of the tube 22 and air therefore is free to flow through the passage 25, into the cross passage 24, into the space 23, and 90 thence to the interior of the sleeve 12, where it passes into the opening 17, thence through the interior of the tubular member 13 into the return pipe. The operation is as follows:

When steam is first admitted to the system after the blowing out operation has been completed air will be forced from the radiator into the interior of the casing and out through the tubular member 13 into the return pipe, the steam follows the air and the steam will collect and condense within the casing in the form of water of condensation. After the water has collected to a degree to reach above the lower end of the sleeve 12 it 110 is obvious that a free passage of steam from the interior of the casing through the member 13 and into the return pipe is no longer permitted. The water of condensation in the casing forms a seal which prevents steam 115 passing between the sleeve 12 and tubular member 13 and through the tubular member to the return pipe. The water of condensation will continue to rise within the casing until it has reached the opening or openings 120 17, and it will then commence to flow through such opening into the tubular member and into the return pipe so that after the water has accumulated to such a height a 125 constant water seal will be maintained with- 130

in the casing which will extend from the floor thereof to the opening or openings 17, thus providing a water seal which will prevent an undue escapement of steam from the 5 radiator into the return pipe and thus serve to seal up and conserve the steam within the radiator and maintain the heating efficiency thereof.

It will be noted that the air vent is above 10 the line which marks the height of the water seal and thus air can always escape above said seal into the space between the sleeve 12 and tubular member 13 and thence through the tubular member into the return 15 pipe. While the opening provided is sufficient to take care of the necessary venting of air from the casing it is not of a size to permit any appreciable amount of steam to escape in this manner.

20 If it is desired to drain the valve, turn the member 18 until the tube 13 is brought clear of the outlet opening 8, as in Fig. 2, after which all of the water within the casing can flow therefrom into the return pipe. This is 25 particularly desirable where the radiator is located upon a porch or other place where a freezing of the water within the valve might take place.

I claim:

30 1. In a valve of the class described, the combination of a casing inclosing a chamber for water of condensation and having an open upper end, said chamber having a bottom outlet and a side inlet between its upper 35 and lower ends, a closure cap for the open upper end of the chamber, said cap comprising an outer section adapted to be threaded into the open upper end of the casing and in close engagement with the end face of the 40 wall of the casing and an independently movable central section threaded into the outer section, the threaded engagement having a sufficient length for a partial withdrawal of the central section without breaking 45 the closure of the cap for the open end of the casing, a sleeve carried by the outer section and depending into the casing chamber with its lower end terminating above the bottom wall of the casing, a hollow 50 member carried by the central section of the closure cap and having an axial passage in communication with the outlet and the cham-

ber of the casing, the lower end of the hollow member projecting into the mouth of the outlet when the central section of the 55 closure cap is fully entered into position, and closing direct communication between the chamber of the casing and the outlet, the partial receding of the central section of the cap withdrawing the end of the hollow 60 member and opening direct communication between the chamber and the outlet without impairing the closure for the upper end of the chamber, substantially as described.

2. In a valve of the class described, the 65 combination of a casing inclosing a chamber for water of condensation and having an open upper end, said chamber having a bottom outlet and a side inlet between its upper 70 and lower ends, a closure cap for the open upper end of the chamber of the casing, said cap comprising an outer section adapted to be entered into and closely engage the wall of the casing at its upper end and an independently movable central section closely 75 entered into and engaging the outer section the length of engagement between the central section and outer section being of sufficient length for a partial withdrawal of the central section without breaking the closure 80 of the cap at the open end of the casing, a sleeve secured at its upper end to the outer section of the closure cap and downwardly extending into the chamber with its lower end terminating above the bottom of the 85 chamber, a tubular member downwardly extending from the central section of the closure cap and passing through the sleeve with its lower end, when the central section of the cap is fully entered, projecting into 90 the mouth of the outlet and closing direct communication between the chamber and outlet and adapted to be raised with the partial withdrawal of the central section of the closure cap and open communication direct 95 between the chamber of the casing and the outlet breaking the closure of the cap, said tubular member having an axial passage with side ports for discharging water of condensation, substantially as described.
